(57) **CLAIM**

The ornamental design for a bubble slide, as shown and described.

DESCRIPTION

FIG. 1 is a rear, right side perspective view of a bubble slide, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and

FIG. 7 is a rear view thereof.

The thin broken lines in the drawings illustrate the portions of the bubble slide, which form no part of the claimed design. The thick broken lines representing stitching are part of the claimed design.
